UNITED STATES PATENT OFFICE.

ABRAHAM GOTTLIEB, OF ERIE, PENNSYLVANIA, ASSIGNOR TO ALBERT D. LEVI AND PHILIP HANAUER, BOTH OF ERIE, PENNSYLVANIA.

KNICKER CUFF.

Application filed August 25, 1924. Serial No. 733,924.

One of the desirable methods of adjusting the cuffs of knickers is by means of a buckle and it is often desirable, particularly for cleaning or washing to remove the buckle. 5 The present invention is designed to improve the method of securing the buckle in such a manner that it may be readily removed when desired and in such a way that the strain on the buckle may be readily sus-
10 tained.

The invention is illustrated in the accompanying drawings as follows:—

Fig. 1 shows a side elevation of the cuff of a knicker.

15 Fig. 2 an end view of the same.

Fig. 3 a perspective view of an ordinary buckle.*

1 marks the knicker, 2 the cuff on the knicker, 3 the slit in the lower end of the 20 knicker and 4 the overlap of the cuff at the slit. A strap 5 is secured at one side of the slit 3 and an opposing strap 6 is sewed to the cuff at the opposite side of the slit. The strap 6 is looped around a bar 7 of a buckle 25 8 and extended under a rear bar 9. The end of the strap 6 has a button-hole 10 and the strap is secured on the button 11 arranged on the cuff. The strap 5 extends under a securing bar 12 of the buckle over the usual 30 bar 13 and under the bar 9.

With this structure the buckle may be readily removed by unbuttoning the end of the strap 6, thus opening the loop formed by this strap around the bar 7. The portion of the strap secured by sewing at 6^a 35 sustains the greater part of the strain because in carrying the loop around the bar 7 the strap is more or less locked against slipping. Thus at most the button can be subjected to only half the strain of the buckle 40 and in ordinary practice is subjected to considerably less than half the strain.

What I claim as new is:—

1. In a knicker cuff, the combination of the cuff band; a buckle; a buckle securing 45 loop looping a part of the buckle having both of its ends secured to the cuff band, one of the ends being permanently and the other detachably secured; and an opposing strap secured to the cuff band and extending into 50 the buckle.

2. In a knicker cuff, the combination of a cuff band; a buckle; a buckle securing strap having one end sewed to the cuff band and the opposite end secured to the cuff band by 55 a button; and a strap secured to the cuff band and extending into the buckle.

In testimony whereof I have hereunto set my hand.

ABRAHAM GOTTLIEB.
